(57) **CLAIM**

The ornamental design for an outboard motor quick connect, as shown and described.

DESCRIPTION

FIG. 1 is a perspective view of an outboard motor quick connect showing the new design;

FIG. 2 is a right-side elevation view thereof;

FIG. 3 is a left-side elevation view thereof;

FIG. 4 is a front elevation view thereof;

FIG. 5 is a back elevation thereof;

FIG. 6 is a top plan view thereof;

FIG. 7 is a bottom plan view thereof;

FIG. 8 is a second perspective view;

FIG. 9 is a second right-side view thereof, showing a closed position;

FIG. 10 is a third perspective view thereof, showing a closed position when in use;

FIG. 11 is a fourth perspective view thereof, showing an open position when in use;

FIG. 12 is a cross-sectional view taken from FIG. 6; and,

FIG. 13 is a fifth perspective view thereof, showing an alternative mounting style.

The broken lines depict portions of the outboard motor quick connect that form no part of the claimed design. The large dashed broken lines enclosing the drawings in FIGS. 10 and 11 form no part of the claimed design.

1 Claim, 12 Drawing Sheets
